UNITED STATES PATENT OFFICE.

WALTER C. WESTAWAY, OF DECORAH, IOWA.

PLUNGER-ROD FOR PUMPS.

SPECIFICATION forming part of Letters Patent No. 397,882, dated February 12, 1889.

Application filed September 8, 1888. Serial No. 284,859. (No model.)

To all whom it may concern:

Be it known that I, WALTER C. WESTAWAY, of Decorah, in the county of Winneshiek and State of Iowa, have invented a new and useful Improvement in Plunger-Rods for Pumps, of which the following is a full, clear, and exact description.

The object of my invention is to relieve reciprocating pumps and pumping machinery of strain and sudden jar in starting and when in rapid operation; and the invention consists of the construction, arrangement, and combination of parts, all as hereinafter described and claimed.

Reference is to be had to the accompanying drawings, forming a part of this specification, in which similar letters of reference indicate corresponding parts in all the figures.

Figure 1 shows my invention applied to a common windmill-pump with handles for starting and for operating by hand. Fig. 2 is a similar view showing a different application of the handle. Fig. 3 is a detailed sectional elevation showing the cushion and coupling. Fig. 4 is a transverse sectional view of the same on line $x-x$ of Fig. 3, and Fig. 5 is a sectional plan view on line $y-y$ of Fig. 3.

A represents the piston or plunger rod of any ordinary windmill-pump held in bearings $a a'$, supported upon the pump-box B. To the upper end of the rod A is attached by bolt b the section C. The upper end of this section is headed, as shown at c . On this section are placed the two plates D D' and the coiled spring or cushion E between said plates.

F represents a rod attached to a windmill or other source of power for operating the pump. This rod is so connected to the plun-

ger-rod A as to act thereon through the cushion E. In this instance it is attached to the plates D D' by a casting, G, formed of a cross-piece, g , and rods $g' g'$, which latter pass through apertures in the said plates D D' and receive nuts at their lower ends, as shown clearly in Fig. 3. The upper surface of the cross-piece g is formed with a frame or socket, g^2 , to receive the lower end of the rod F and bolts f , as shown in Fig. 1. The section C is provided with the collar H, held by set-screw h , for supporting the plate D and taking the down-thrust of the rod F.

The handle J, Fig. 1, is the handle of an ordinary pump. In Fig. 2 this handle is attached to the rods g' , so when operated it will act through the spring E.

Having thus described my invention, what I claim as new, and desire to secure by Letters Patent, is—

In a pump-rod, the combination, with the head G, having a recess in its lower face and two depending rods, $g' g'$, of the two plates D D', having end apertures through which said rods pass, and also having aligned central apertures, the nuts on the lower ends of rods g' , the section C, extending up through said central apertures and having a flange, c , on its upper end above the top plate, D, and within the recess in the head, the collar on the section C under plate D', and a single coiled spring on the section C, between the two plates D D', and alternately compressed thereby, substantially as set forth.

WALTER C. WESTAWAY.
